DESIGN FOR A MAN'S SHORTS

Philip Friedman, New York, N. Y.

Application April 17, 1945, Serial No. 119,065

Term of patent 14 years

(Cl. D3—17)

To all whom it may concern:

Be it known that I, Philip Friedman, a citizen of the United States, residing at New York, in the county of New York and State of New York, have invented a new, original, and ornamental Design for Man's Shorts, of which the following is a specification, reference being had to the accompanying drawing, forming part thereof.

I claim:

The ornamental design for a man's shorts, as shown.

PHILIP FRIEDMAN.
